FASTENER

George Brown, Chicago, Ill.

Application February 28, 1944, Serial No. 524,193

5 Claims.

(Cl. 292—67)

The present invention relates to fasteners, and more particularly to a device capable of serving simultaneously as a lock and a fastener or individually in either capacity.

An object of the present invention is to provide a novel fastener which is simple in its construction, adapted to be manufactured at low cost, and readily adapted to be used for fastening and locking windows, screens, doors, shutters and the like.

The present contribution is predicated on the desire to produce a simple, inexpensive, sturdy and effective locking fastener easily attached and simple to manipulate.

More particularly, this invention comprehends a reversible fastening device capable of being attached on either the right or left side of the object or at the top or bottom thereof.

Another object of this invention is to provide a fastener made of flexible material such as spring steel which renders the device capable of yielding in order that it may become properly engaged in any desired fixed position. Once the fastener is so placed in locked position, its resiliency necessarily draws the movable object, such as the window, screen or door, closely and firmly to the frame which engages the fastener.

This spring action prevents the object attached from moving, shifting or rattling. If used on a screen, window or the like, it is obvious that this feature will serve to keep the object rigidly and snugly in place, thereby avoiding cracks or openings which usually result from loose attachments.

A still further object of this invention is to provide a simple fastening device which can be readily adapted for use on a large variety of objects with a minimum effort and eliminate cumbersome and less effective means now in use. One example is window screens as commonly used today. They are usually attached to the window casings by such means as narrow strips nailed to the casing so positioned that these strips engage the screen through grooves on the sides of the screen. The strips are necessarily of light construction and are easily broken or displaced and the screens are weakened by the grooves in the frames. Such frames are easily broken and rendered entirely useless. The present invention provides a device which overcomes these objectionable features. While this device is cheaper and more easily attached, it is also much more effective as it not only makes the screen fit snugly but prevents it from being opened from the outside, which is possible with the means commonly in use today. The benefits illustrated by this

example can be duplicated with many other objects to which the present invention can be readily adapted with equal utility.

It is also contemplated that this invention be used as a fastener on items such as luggage, shoes, and the like. While it is preferred that this device be made of material such as spring steel and wire, a variety of other materials, such as elastic and plastics, can be employed depending upon the specific use to which the fastener is applied.

Other objects, features, capabilities and advantages are comprehended by the invention as will later appear and as are inherently possessed thereby.

15 Referring to the drawing:

Figure 1 is a fragmentary view in perspective of a window casing with an associated screen wherein a locking mechanism made in accordance with the present invention is embodied and shown in unlocked condition;

20 Figure 2 is a view similar to Figure 1 of the drawing showing the fastener in locked condition;

Figure 3 is a view in cross section taken in the plane represented by lines 3—3 of Figure 2 of the drawing;

25 Figure 4 is a horizontal fragmentary view in cross section of an assembly such as shown in Figure 1 of the drawing showing the locking mechanism associated with the bottom member thereof;

30 Figure 5 is a front view of a modified form for a locking device made in accordance with the present invention;

35 Figure 6 is a front view of another modified form for a locking device made in accordance with the present invention; and

Figure 7 is a front view of still another modified form for a locking device made in accordance with the present invention.

40 Referring now more in detail to Figures 1 and 2 of the drawing, an embodiment selected to illustrate the present invention and generally referred to by reference numeral 8 is shown as comprising fastening means for securing a screen 10 in proper position with respect to a window casing 12.

45 The present invention is directed more particularly to a novel fastening means for providing a tight joint between the screen and window casing and in the preferred embodiment of the invention as shown in Figures 1 and 2, the fastening means comprises an elongated holding element 20 which may be cut from a sheet of spring steel having formed at one end a rolled hinge

element 22 and being provided adjacent its other end with one or more openings 28 adapted to receive screws or the like 26 adapted to secure the said holding element to said screen. Said rolled hinge element 22 is adapted to slidably and hingedly receive latch element 16. The latch element 16 is preferably formed from spring wire to provide a central portion 17 embraced by the hinged element 22 of the holding element 20. The free ends of the spring wire are bent to form loops 34 providing an opening in the latch element having its greatest dimension at the center 18 adapted to receive the headed keeper 14 which is mounted in the casing 12. The free ends of the wire defining the loops 34 converge with respect to the central portion 17 to provide wedge or cam surfaces engageable with the keeper 14 acting to draw the screen 10 into tight relation with the casing 12 when the latch member 16 is moved relative to holding member 20 when in embracing relation to the keeper 14. One of the free ends of the wire, as at 30, may be bent angularly with respect to the plane of the latch member to provide a finger grip for manipulation of the latch member.

It will be appreciated that the present fastener provides a tight joint between the screen and the casing. Such tight connection between the screen and casing is accomplished by providing the latch with an inclined portion which effectively draws the screen closely to the casing when said latch is forced to a closed or locked position. Figure 3 of the drawing illustrates member 20 flexed under the action of the latch member to assure a tight fit between the screen and casing at all times.

This flexing of member 20 facilitates the initial engagement of the latch to the keeper 14. The resilient action of member 20 is supplemented by the method in which it is attached to screen. As disclosed in the drawing, one end of this member is attached to the screen while the opposite end, formed with the hinge means to support the latch, remains entirely detached, thus allowing the free end to yield more readily when force is applied to the latch.

In addition to being an effective fastener, this invention also serves as a locking device as shown in Figure 4. Here the holding element 20 is mounted on the bottom horizontal portion of the screen frame 10 and the keeper 14 is fixed on the sill or base 32 of the casing. By mounting the fastener in this manner, the screen or window is locked from the inside and cannot be opened from the outside by sliding it upwardly. If desired, the fastener may be similarly mounted at the top of the screen 10 for engagement with a suitable keeper mounted in the top of the casing 12.

The preferred embodiment of the invention as shown in Figures 1 through 4, inclusive, as well as in Figure 5 of the drawing is formed with oppositely disposed loops having keeper engaging surfaces to adapt the device for right or left hand mountings. Referring to this figure, it will be noted that latch 16 is inserted in the cylindrical hinge portion 22 of holding element 20. The latch is capable of being slidably moved upwardly or downwardly from its normal position and is accordingly adjusted for use on either the right or left side of the screen, window or other object sought to be secured to the casing or frame. It is also obvious that this reversible or interchangeable feature renders it possible to apply the fastener to the top or bottom of the desired members. In Figure 5 the latch is illustrated with

an additional modification. The loops 34 are formed with notches 37 having shoulders 35 adapted to receive keeper 14. Since the engaging surface of latch 16 is provided with a cam surface to produce a tight locking effect, the latch may under certain conditions of strain tend to creep back to the position of least stress. Forcing the latch into locked position and causing the keeper 14 to become lodged in the notch or depression 37 prevents the latch from becoming disengaged from its closed position.

As a further modification of a fastening device made in accordance with the present invention, the device may be formed as shown in Figure 6 of the drawing to include a securing element 20 and a latch element 36 slidably and hingedly connected together in the manner disclosed in the embodiments hereinbefore described. In this form the latch element is provided with a single loop 39 and accordingly the device is not reversible as are the previously described fasteners.

While various embodiments of the invention as shown in Figures 1 to 6 have been described in connection with their use as fastening means for screens, doors, windows and the like, it will be readily apparent that the fasteners are capable of being used for a large variety of purposes. The novel feature of a fastener having a slidable latch with a cam surface adapted to effect a firm closure will find many additional uses. Figure 7, for example, illustrates a further modified form capable of being used on such objects as shoes, luggage and similar articles. As there illustrated, holding element 38 is constituted as an elastic or similar resilient material which can be readily attached by sewing, riveting or the like to one of the objects 40. Latch 42 is attached at 44 to element 38. The adjacently disposed object 46 supports keeper 48 which is adapted to engage latch 42 whereupon the same fastening or locking is accomplished as shown in the previous illustrations.

While I have herein described and upon the drawing shown an illustrative embodiment of the invention, it is to be understood that the invention is not limited thereto but may comprehend other constructions, arrangements of parts, details and features without departing from the spirit of the invention.

I claim:

1. In combination, a plurality of adjacently disposed members, a fastening device therefor, comprising latch mechanism including a plurality of flexible elements hingedly and slidably connected together for relative movement with respect to one another, one of said elements having means for securing said device to one of said members, and another of said elements being formed to embrace a keeper secured to the other of said members and having means operable upon sliding movement thereof relative to said first named element to engage said keeper for drawing said members into tight relation to one another.

2. A fastening device, comprising a plurality of resilient elements hingedly and slidably connected together, one of said elements having securing means, another of said elements being formed to provide means for embracing a keeper, said last named means having means angularly disposed with respect to the axis of said hinge connection for wedgedly cooperating with said keeper.

3. A fastening device, comprising a plurality of elements hingedly and slidably connected to

gether, one of said elements having securing means, another of said elements being of resilient material and formed with an opening adapted to receive a keeper, said opening being defined in part by a cam surface angularly disposed with respect to the axis of said hinge connection for wedgedly cooperating with said keeper.

4. A fastening device for securing together adjacently disposed members, comprising latch mechanism including an element of resilient material having means for securing said device to one of said members, said element having hinge means, and said mechanism further including an element having hinge means cooperating with said first named hinge means for movement with respect to said first named element, said second named element being characterized as having means adapted to embrace a keeper mounted on the other of said members and including cam means engageable with said keeper to draw said members into juxtaposition to one another upon relative movement of said second named element with respect to said first named element and upon flexing of said first named element.

5. A fastening device for securing together adjacently disposed members, comprising latch mechanism including a securing element of resilient material having attaching means adjacent one end thereof for securing said device to one of said members, said element having its other end rolled to provide a hinge element disposed in substantial spaced relation to said attaching means, said mechanism further including a latch element formed from wire to provide a centrally disposed portion slidably and hingedly received by said hinge element, said wire further having its free ends angularly disposed with respect to said central portion to provide a latch element of looped construction adapted to embrace a keeper mounted on the other of said members, the said angular disposition of one of said free ends being such as to wedgedly engage said keeper upon relative slidable movement with respect to said securing element for drawing said one of said members into tight relation to the other of said members through the medium of said resilient securing element.

GEORGE BROWN.
